UNITED STATES PATENT OFFICE.

HENRY D. ROGERS, OF GRAFTON, OHIO.

IMPROVEMENT IN SECURING POINTS TO PLOWS.

Specification forming part of Letters Patent No. 30,352, dated October 9, 1860.

To all whom it may concern:

Be it known that I, HENRY D. ROGERS, of Grafton, in the county of Lorain and State of Ohio, have invented a new and Improved Mode of Securing Points to Plows; and I do hereby declare that the following is a full and exact description thereof, reference being had to the accompanying drawings, and to the letters of reference marked thereon.

The nature of my invention consists in providing the forward portion of a plow with a steel or hardened point, the upper lip of said point extending back and above the forward portion of the plow, and the under portion of said point extending the entire length of the lower portion of the landside of said plow, and is there secured by means of lips and set-screws, in a manner hereinafter specified.

To enable others skilled in the art to make and use my invention, I will proceed to describe its construction and operation.

My invention may be made applicable to any of the known forms of plows by making the shoe longer or shorter, as the case may require, said shoe being shown at A, Figs. 1, 2, 3, and 4 in the accompanying drawings. At the forward end of the shoe, at B, Figs. 1, 2, and 3, I put a piece of tempered steel to form a point. A portion of said piece of steel is extended up over the forward end of the plow, as shown at C', Figs. 1 and 3, a vertical view of said point being shown at C'', Fig. 2. The back end of the aforesaid shoe is provided with a split hook, (marked D,) Figs. 1, 2, and 3. Between the split in the hook, and the lower turn in the hook is placed a set-screw, (marked E, Figs. 1, 2, 3, and 4.)

I will now show the manner of putting said point and shoe onto the plow for operation.

I place the thin back portion of the landside J into the split portion of the hook, (marked F, Fig. 2.) I then slide the point B over the forward end of the plow, as shown at Figs. 3 and 4. I then tighten the said point and shoe by means of the set-screw E. The forward end of the plow may be made rough or pointed, so that the steel point cannot be displaced without turning back the set-screw E. Fig. 4 shows a plow inverted for the purpose of showing the lower part of the point and shoe. By this arrangement it will be seen that one point can be used for more than one plow, as there is no hole to be drilled in the cast-iron, it being made too hard to drill without much labor and time being spent. By using my improvement a point may be new laid with steel, and made to last a great while longer than it otherwise would; and as the point always wears more on the under side than it does on the upper side, a plow-point requires to be often dressed, so that it is quite an object to get some mode of attaching and detaching the point with facility.

Having thus described my improved point and shoe, what I claim as new, and desire to secure by Letters Patent, is—

The securing the point B by means of the shoe A, hook D, and set-screw E, the whole being arranged in the manner and for the purpose as herein described.

HENRY D. ROGERS.
